UNITED STATES PATENT OFFICE.

BENJAMIN B. BETTS, OF ST. LOUIS, MISSOURI.

GUARD-RAIL MOUNTING.

1,155,992.

Specification of Letters Patent.

Patented Oct. 5, 1915.

Application filed December 21, 1914. Serial No. 878,298.

To all whom it may concern:

Be it known that I, BENJAMIN B. BETTS, a citizen of the United States, and resident of St. Louis, Missouri, have invented certain new and useful Improvements in Guard-Rail Mountings, of which the following is a specification containing a full, clear, and exact description, reference being had to the accompanying drawings, forming a part hereof.

My invention relates to improvements in guard rail mountings, in which a unitary structure is formed by rolling or pressing comprising a seat for a running rail, a seat for a guard rail, in a plane above and partially overlying the running rail seat, an element forming recesses to receive the bases of the two rails and a brace extending to a point where it will engage beneath the ball of the running rail, flanges or shoulders on said seats in opposition to said recesses, anticreeping devices on the bottom of the mounting and through which mounting spike openings are formed for holding the rails to the mounting and the mounting to the ties or sleepers.

The object of my invention is to construct a guard rail mounting having the characteristics just recited, by rolling or pressing in order to produce a mounting of material capable of withstanding the strains it is subjected to in use and at a minimum of cost.

With the above object in view, my invention consists in the novel details of arrangement and construction of the parts of the mounting as will be fully set forth in my specification, specifically pointed out in my claims and illustrated by the accompanying drawings, in which—

Figure 1 shows in plan a guard rail mounting embodying my improvements having two rails shown thereon, as in use; Fig. 2 is an end elevation of the mounting as shown in Fig. 1, the two rails being shown in section; Fig. 3 is a perspective showing the mounting as formed by rollers; Fig. 4 is an edge view of the mounting, on a reduced scale, as formed by rollers; Fig. 5 is a view similar to Fig. 4, showing a second step in the forming of the mounting; and Fig. 6 is a view similar to Figs. 4 and 5, showing the final forming.

Referring by numerals to the accompanying drawings: 10 designates that portion of the mounting whose upper surface constitutes the seat for the running rail 11, and

12 designates that portion of the mounting whose upper surface constitutes the seat for the guard rail 13. To the right and left, respectively of these two seats are the 60 rail base shoulders 14 and 15.

The guard rail seat is in a plane above the running rail seat and partially overlaps the same, so that standard, unaltered rails may be employed. For example, I may use a 65 standard one hundred pound running rail and an eighty pound guard rail and the elevation and lateral positioning of the guard rail seat relative to the running rail seat properly spaces the ball of the guard rail 70 laterally from the ball of the running rail.

In order to simply save material, I form in the mounting beneath the guard rail seat, a depression 16, which divides the mounting and forms the two tie engaging 75 surfaces 17 and 18. In order to prevent creeping of the mounting over the tie, I provide the ribs 19.

As shown in Figs. 3 and 4, the mounting is first formed by rolling or pressing 80 from a single ingot with a web 20 arising from the guard rail seat 10. This web is then bent to parallel the rail seats (as shown in Fig. 5), to form the recess 21 which receives the base of the running rail and to 85 extend the guard rail seat 12 over the running rail seat. The web 20 is then bent backwardly over itself to form the recess 22 which receives the base of the guard rail. The web is then reversely bent from the recess 22 to form a brace 23 extending upwardly and laterally so that its end will lie beneath the ball of the running rail. 90

In order to facilitate the bending of the web from its vertical position to the horizontal, I cause to be formed in its side near its base a groove 24 (see Fig. 4).

The salient feature of this guard rail mounting is its being made, with the characteristics described, by rolling or pressing 100 from an ingot.

Having thus described my invention, what I claim as new therein and desire to secure by Letters Patent of the United States, is:

1. A guard rail mounting provided with 105 a running rail seat, a flange therefor, a guard rail seat and a flange therefor, said seats occupying different elevations and overlapping each other, and a brace interposed between said seats adapted to lie beneath the ball of the running rail, all rolled or pressed from a single piece of material. 110

2. A guard rail mounting provided with a running rail seat, a shoulder therefor, a guard rail seat and a shoulder therefor, said respective seats occupying different elevations and overlapping each other, thus permitting the use of a standard unaltered running rail and a guard rail, there being spike openings formed adjacent the shoulder on the running rail seat and on the 13 guard rail seat, and a brace interposed between said seats and projecting upwardly

therefrom at an angle and adapted to seat beneath the ball of the running rail, said mounting all rolled or pressed from a single piece of material.

15

In testimony whereof, I have signed my name to this specification, in presence of two subscribing witnesses.

BENJAMIN B. BETTS.

Witnesses:

EDWARD E. LONGAN,
E. L. WALLACE.
